UNITED STATES PATENT OFFICE

GUSTAV F. C. BAUER, OF TONAWANDA, NEW YORK, ASSIGNOR TO NATIONAL POLICE SIGNAL COMPANY, OF BUFFALO, NEW YORK, A CORPORATION OF NEW YORK

SOUND REPRODUCING APPARATUS

Application filed October 15, 1929. Serial No. 399,786.

This invention relates to a sound reproducing apparatus and more particularly to that type of phonograph in which the sound is reproduced through a needle traversing a hard record which has been formed through the original rendition of the music or other sounds to be reproduced although the invention can also be employed in reproducing sounds directly as from a diaphragm or from any other form of record.

One of the principal objects of this invention is to provide such a device which will give a faithful and clear reproduction of the sound recorded on the record through electrical means, and in which in particular, the full range of vibrations and overtones are reproduced exactly as originally produced, such overtones being usually lost in the mechanical reproduction of sound.

Another aim is to provide such a reproducer in which the elements vibrated by the needle traversing the record are light in weight so as to be sensitive to the slighter vibrations of the needle.

A further aim is to provide an electrical sound reproducer in which the reproduction is effected through the microphonic action of an electron tube, such as are used in radios. By rigidly holding all but one of the elements of an electron tube and vibrating the other through a prepared record or the like, the audio-frequency impulses from the tube can be amplified to give a clear and undistorted reproduction of the sound.

Another object is to provide such a sound reproducing apparatus which employs any well known audio circuit. By this means the invention is particularly applicable to radio-phonographs since the same audio circuit can be used for both the radio and the phonograph.

Another purpose is to so mount the electron tube as to be extremely sensitive to the vibrations of the needle and is so mounted that it can be easily replaced, and new needles inserted as they become worn.

Other aims are to provide such an apparatus which can be produced at low cost, is durable and in which, in particular, the three ele-

ment electron tube will stand up under severe and constant use.

In the accompanying drawings:

Figure 1 is a diagrammatic view of a suitable form of audio circuit showing the manner in which a three element electron tube and an electrical reproducer or loud speaker can be arranged to reproduce sounds in accordance with my invention.

Figure 2 is a side elevation of a tone arm, partly broken away, showing the manner in which the three element electron tube is mounted and vibrated through a record.

Figure 3 is a fragmentary top plan view of the tone arm.

Figures 4-9 are sections taken on the correspondingly numbered lines on Figure 2.

Figure 10 is a front elevation of the tone arm, showing part of a three element electron tube guard or housing broken away to expose the tube.

Figure 11 is a fragmentary enlarged view similar to Fig. 2, showing the manner in which the needle is connected to the three element electron tube.

Similar reference numerals refer to like parts in each of the several views.

In its general organization, this invention comprises an audio circuit including a reproducer or loud speaker and a three element electron tube which tube and reproducer are operatively connected so that the audio-frequency impulses from the tube are transmitted to the reproducer, a structure within the tube for rigidly holding two of the tube elements, preferably the filament and the plate, against vibration and the grid being mounted so as to vibrate with the tube and a needle removably carried by the tube and adapted to traverse the track of a record so that the vibrations recorded on the record are transmitted to the vibratory grid. The vibration of the grid varies the electron flow and the audio frequency impulses from the tube, when reproduced by the reproducer give a faithful reproduction of the sounds recorded in the record.

While a three element electron tube is preferred it will be understood that a two or

four element electron tube can also be employed.

The invention also comprehends a specific manner of mounting the electron tube on a tone arm of a phonograph and a specific construction of a three element electron tube by which the slighter vibrations and overtones are accurately reproduced and the tube and needle are readily replaceable as they become worn.

The invention is shown as used in connection with a phonograph having a revolving table 15 which is supported on a shaft 16, this shaft serving to center a disk record 17 of hard rubber or the like and being revolved by an electric motor 18. The record is formed with the usual track for guiding a needle 19 and the track is formed so as to vibrate the needle 19 in response to the sounds recorded on the record.

The primary conception of this invention resides in the employment of the microphonic action of a two, three or four element electron tube to produce audio-frequency vibrations by the vibration of one element of the tube relative to the others. A three element electron tube 20 suitable for this purpose is shown, the same including the usual Bakelite base 21 which is preferably of irregular form for a purpose which will presently appear, and a glass bulb 22 which houses a filament 23, grid 24 and plate 25. These are shown in Fig. 1 as connected to an audio circuit, the tube being connected to the audio circuit in the same manner as a detector tube in a radio audio circuit. In the circuit shown, the grid 24 is negatively charged from the "C" battery through the wire 26; the plate 25 is positively charged from the "B" battery through the wire 27 which connects with the first audio transformer 28 and in turn is connected by wires 29 and 30 with the positive terminal of the "B" battery, and the terminals of the filament 26 are respectively connected with the negative terminal of the "A" battery through the wire 31 and to the positive side of the "A" battery through the wire 32.

In all present radio electron tube installations, the output impedance is controlled and varied by the grid potential changes. In the present application, the output impedance is varied by mechanically shifting the position of the grid in relation to the filament and the plate without changing the relative potential of the grid. When the grid or any other single element of a charged electron tube is so shifted or vibrated with respect to the other elements, the flow of electrons from the filament to the plate is correspondingly affected and when the grid is mechanically vibrated at audio-frequencies corresponding audio-frequency fluctuations occur in the plate current. This vibration of the elements of an electron tube and its

effect upon the action of the tube is known as the microphonic action of the tube. These audio-frequency fluctuations when amplified through the usual first and second audio transformers 28 and 33 and amplifying electron tubes 34 and 35 cause corresponding sounds to be reproduced in the reproducer or loud speaker 36.

According to the preferred form of the present invention two of the tube elements, the filament and the plate, are anchored against movement to prevent any sympathetic vibration, and the third, the grid, is caused to follow faithfully the vibrations of a phonograph record or the like so that the audio-frequency fluctuations caused in the audio-circuit will effect a reproduction of the recorded sounds in the reproducer 36.

The base 21 of the three element tube 20 is arranged in a socket 37 formed at the outer end of a tone arm 38, this tone arm being preferably made of Bakelite or the like and being hollow to form a conduit receiving the wires 26, 27 and 31 and 32 which connect with the elements of the tube 20. This socket 37 conforms to the shape of the base 21 of the electron tube 20 which it receives and since the shape of both are irregular the base can be received in one position only thereby insuring the proper positioning of the electron tube in the socket 37. This tone arm is preferably supported by a horizontal pivot pin 39 between two ears 40 which permit the vertical movement of the tone arm and the two ears 40 are carried by a pintle 41 which is journaled in a base 42, so that the tone arm can follow the track of the record 17. Any form of tone arm mounting can, however, be employed.

On each inner side of the socket 37 of the tone arm, a spring contact 43 is arranged in a suitable recess, each of these contacts being connected with one of the wires 26, 27, 31 and 32 and engaging one of the contacts 44 at the sides of the base 21 of the three element electron tube. These contacts 44 are connected to the filament, grid and plate of the tube and the spring contacts 43 in addition to forming electrical contacts also serve as a spring mounting for the tube which is vibrated in response to the recorded vibrations as hereinafter described. The base 21 of the tube 20 is also spring supported at its rear by a small helical spring 45.

Within the glass bulb 22 are arranged two comparatively heavy supporting wires 46 which are suitably anchored in the Bakelite base 21 and at their outer ends are rigidly connected to a cross member or bar 47 made of mica or other nonconducting material. To this mica cross bar are rigidly anchored the outer ends of the plate 25 and the filament 23 by means of small pins 70 or the

like so that these elements are held against vibration.

The outer end of the glass bulb 22 is formed to provide a nipple 48 which receives a stem 5 or anchor 49. This stem is rigidly mounted in the nipple 48 and projects inwardly through an opening 50 in the mica cross piece 47, and to the end of the stem 49 the outer end of the grid 24 is anchored. The opening

10 50 is sufficiently large to permit the stem 49 to vibrate independently of the cross piece 47 and thereby insures the vibration of the grid in response to the vibration of the tube 20. To insure the vibration of the grid in response 15 to very slight vibration of the tube, the other or inner end of the grid is preferably connected to its lead or the terminal of the wire 26 by a flexible link 51.

On the underside of the socket 37 two ears 20 52 are formed which project downwardly and carry outwardly projecting pins 53. These pins engage bayonet slots 54 formed at the rim of a protecting casing 55 which houses the three element tube 20 and can be made 25 of any suitable non breakable material. At its upper end an annular row of ventilation openings 56 is provided and at its lower end or tip a relatively large opening is provided which is covered by a flexible diaphragm 57. 30 This diaphragm can be made of any suitable material such as rubber and is shown as held in place by a retaining collar 58.

A needle holder 59 projects through this diaphragm 57 this needle holder having an upper cup shaped portion 60 which is firmly cemented or otherwise secured to the nipple 48 of the three element tube 20 and a lower part which receives the needle 19, this needle being shown as held in place by a set screw 40 61. The needle holder is preferably supported by the flexible diaphragm, the diaphragm engaging a reduced part of the needle holder.

With the parts arranged as described, the 45 operation of the apparatus in reproducing sound from the record 17 is as follows:

The record 17 is turned by the motor 18 and vibrates the needle 19 following its track, this needle being held against the record by the 50 weight of the tone arm 38 and its associated parts. The vibration of the needle 19 in turn vibrates its needle holder 59 and the three element electron tube 20 and since the needle holder is supported for vibratory movement by the flexible diaphragm 57, and since the 55 base of the three element electron tube is spring supported in its socket by the four contact springs 43 and the helical spring 45, the entire tube 20 is sensitive to very slight vibrations of the needle 19 and will vibrate in unison therewith.

The filament 23 and plate 25 are rigidly supported in the tube 20 by their connection with the mica cross bar 47 of the wires 46 60 which extend outwardly from the base and

hence these elements of the tube are prevented from vibrating. The grid 24 is, however, connected with the vibratory tip of the tube by the stem 49 of the tube 20 and further by reason of its flexible connection to its lead 70 26 by the flexible link 51 is vibrated in response to the vibration of the needle 19.

The grid 24 is negatively charged from the "C" battery and its vibration between the incandescent filament 23 and the positively charged plate 25, effects a corresponding variation in the flow of electrons from the filament to the plate and thereby effects a corresponding variation in the audio-frequency impulses of the tube, these impulses are then amplified by any suitable form of audio circuit, such as shown in Fig. 1 and are reproduced as sound by a reproducer or loud speaker 36.

An electron tube having all but one of its 85 elements held against vibrating and the other subject to the vibrations of the tube, when connected with an audio circuit as described, will give a clear and faithful reproduction of the sound vibration imparted to 90 it and will accurately and clearly reproduce the slighter vibrations and overtones as well as the more dominant vibration. It is also apparent that the invention is particularly applicable to radio-phonographs since the 95 same audio circuit can be used in amplifying and reproducing both for the radio and the phonograph by the provision of suitable switching means, the three element electron tube 20 of the present invention taking the 100 place of the detector tube in the radio circuit. The tube of the present invention and its associated parts are also simple and inexpensive in construction, will stand up for a long time, and are easily replaced as may be required. 105 While a three element electron tube is specifically described, it will be understood that a four element or a two element tube can also be employed, but a three element tube is preferred.

Having fully described my invention, I 110 claim:

1. A sound reproducing apparatus comprising an audio-circuit including a reproducer and an electron tube, having at least 115 two elements, said tube and reproducer being operatively connected so that audio-frequency impulses from said tube are transmitted to said reproducer, said tube including a base supporting one end of said elements, a glass bulb and a supporting structure anchored in said base, composed of a pair of supporting wires and a cross piece of insulating material connected to the ends of said supporting wire, means anchoring all but one of the elements of said tube to 120 said cross piece and means for vibrating the other element of said tube.

2. A sound reproducing apparatus comprising an audio-circuit including a repro- 125

ducer and an electron tube having at least two elements, said tube and reproducer being operatively connected so that audio-frequency impulses from said tube are transmitted to said reproducer, a means for supporting all but one of the elements of said tube against vibration, means connecting the opposite ends of the other element of said tube to the tip of said tube and means connected to the tip of said tube for vibrating said tube.

3. A sound reproducing apparatus comprising an audio-circuit including a reproducer and an electron tube having at least two elements, said tube and reproducer being operatively connected so that audio-frequency impulses from said tubes are transmitted to said reproducer, a means for support all but one of the elements of said tube against vibration, means connecting the opposite ends of the other element of said tube to opposite parts of the body forming said tube to vibrate therewith and means for vibrating said tube.

4. An electron tube comprising a base, a bulb, at least three elements arranged in said bulb and comprising a filament, a grid and a plate each connected to said base, a pair of supporting wires arranged in said bulb and enclosed in said base, a cross piece of insulating material connecting said cross wires, means anchoring said filament and plate to said cross piece and supporting said filament and plate against vibration and means connecting said grid to said bulb, said grid being mounted to vibrate relative to said plate and filament and said bulb being formed to provide means for attaching a vibrating element thereto.

5. A sound reproducing apparatus comprising an audio-circuit including an electron tube having at least two elements, and a reproducer, said tube and reproducer being operatively connected so that audio-frequency impulses are transmitted from said tube to said reproducer, one of the elements of said tube being movable relative to the other, a tone arm supporting the wires connecting said tube and reproducer and having a socket formed at its outer end, means for yieldingly supporting said tube within said socket, the contacts of said tube contacting with the contacts of said wires, a guard removably secured to said tone arm and enclosing and protecting said tube, said guard being provided with an opening, a record, and a needle removably carried by said tube and projecting through said opening, said needle being adapted to be vibrated by said record.

In testimony whereof I affix my signature.
GUSTAV F. C. BAUER.
